UNITED STATES PATENT OFFICE.

GEORGE D. HECK, OF PRINCE BAY, NEW YORK, ASSIGNOR TO THE S. S. WHITE DENTAL MANUFACTURING COMPANY, A CORPORATION OF PENNSYLVANIA.

DESIGN FOR A DENTAL-EQUIPMENT STAND.

59,650.

Specification for Design.

Patented Nov. 15, 1921.

Application filed December 29, 1920. Serial No. 433,951. Term of patent 14 years.

To all whom it may concern:

Be it known that I, GEORGE D. HECK, a citizen of the United States, and a resident of Prince Bay, in the county of Richmond, State of New York, have invented a new, original, and ornamental Design for Dental-Equipment Stands, of which the following is a specification, reference being had to the accompanying drawing, forming part thereof.

The drawing represents a front elevational view of a dental equipment stand showing my new design.

I claim:

The ornamental design for a dental equipment stand, as shown.

In testimony whereof I have hereunto set my hand this 21st day of December, A. D. 1920.

GEORGE D. HECK.
